Patented July 27, 1920.

Inventor
H. J. REED.
By *A. Randolph, Jr.* Attorney

UNITED STATES PATENT OFFICE.

HENRY J. REED, OF SEATTLE, WASHINGTON.

GARMENT-SUPPORTER.

1,347,911.

Specification of Letters Patent. Patented July 27, 1920.

Application filed November 8, 1918. Serial No. 261,664.

To all whom it may concern:

Be it known that I, HENRY J. REED, a citizen of the United States, residing at Seattle, in the county of King and State of Washington, have invented certain new and useful Improvements in Garment-Supporters; and I do hereby declare the following to be a full, clear, and exact description of the invention, such as will enable others skilled in the art to which it appertains to make and use the same.

My invention relates to improvements in fastening devices and more particularly to means for supporting hose.

15 An important object of this invention is to provide a hose supporter comprising a pair of coacting gripping devices adapted to be applied to the limbs in a highly convenient and expeditious manner.

20 A further object of the invention is to provide a device of the character described, which is simple, neat in appearance and cheap to manufacture.

Other objects and advantages of the invention will be apparent during the course 25 of the following description.

In the accompanying drawings forming a part of this specification and in which like numerals are employed to designate like 30 parts throughout the same,

Figure 1 is a front elevation of a fastening device embodying my invention, showing the same supporting a sock,

Fig. 2 is a similar view of my improved 35 hose supporter showing the same prior to being locked in engagement with a sock,

Fig. 3 is a front elevation of a hose engaging member embodying the invention, and,

40 Fig. 4 is a front elevation of a coacting locking member embodying the invention.

In the drawings wherein for the purpose of illustration is shown the preferred embodiment of my invention, the numeral 10 45 designates a sock engaging member of a single length of wire bent intermediate its ends to form parallel arms 11 and a relatively long bight portion 12, the latter being curved longitudinally to conform to the 50 configuration of the limb. The end portions of the length of wire 10 are bent to form horizontal portions 13 having L-shaped arms 14 extending therefrom. The horizontal arms 13 are secured by suitable

stitching to a pad 15 adapted to space the 55 sock engaging member 10 from the flesh.

A coacting sock engaging member 16, clearly shown in Fig. 4, is made from a sheet of relatively light metal and is curved longitudinally to conform to the configuration of the limbs. The same is provided with a longitudinally extending slot 17 in its lower portion thereof. A locking plate 18 provided with a curvature similar to the plate 16 is arranged on the outer side of the 60 plate 16 and is provided along its upper edge with a longitudinally extending hinged barrel 19. A hinged pin 20 secured to the member 16 by rivets 21 extends through the barrel 19 and effects a hinge connection between the plates 16 and 18. When in a downward position, the locking plate 18 extends over the greater portion of the elongated opening 17.

As shown in Fig. 2, when it is desired to 75 engage my improved fastening device with a sock, the member 10 is first passed between the limb and the upper portion of the sock. The upper portion of the sock arranged over the bight portion 12 is now 80 passed through the elongated opening 17 in the base plate 16. The bight portion 12 of the sock engaging member 10 is pressed downwardly or outwardly through the elongated slot 17 sufficiently far enough to permit of the locking plate 18 to be swung 85 downwardly and flush with the base plate 16. Upon the locking plate 18 assuming this position, the bight portion 12 is drawn over the outer side of the locking plate 18 90 and thus the sock is securely fastened as shown in Fig. 2.

While I have shown and described the preferred embodiment of my invention, it is understood that I may make such minor 95 changes in arrangement and construction of parts, as will remain within the spirit of the invention and the scope of the appended claims.

Having thus described my invention, 100 what I claim is:—

1. A device of the character described, comprising, a garment engaging member, a pad upon which the garment engaging member is arranged; a base plate adapted 105 to be arranged outwardly of the garment engaging member and having an elongated opening therein; a portion of said garment

engaging member being adapted to extend through said elongated openings; and a locking plate adapted to lock said garment engaging member upon its entrance into 5 said elongated opening.

2. A device of the character described, comprising, a longitudinally curved base plate having an elongated opening in its lower end portion thereof; a garment engaging device formed from a single length of metal including a pair of parallel legs and an intermediate bight portion, the bight portion of said garment engaging device being adapted to extend through the elongated opening in said base plate; and 10 means to lock the garment engaging member upon the entrance of the bight portion into the elongated opening in said base plate.

3. A device of the character described, comprising, a longitudinally curved base plate having an elongated opening in its lower end portion thereof; a garment engaging device formed from a single length 25 of metal bent to afford a pair of parallel legs and an intermediate bight portion, the bight portion of said garment engaging device being adapted to extend through the elongated opening in said base plate; and 30 a longitudinally curved locking plate hingedly secured to the longitudinally curved plate, said longitudinally curved locking plate being adapted to engage the garment engaging device upon the entrance of the 35 bight portion into the elongated opening in said base plate.

4. In a garment supporter, a supporting plate of a shape to conform to the leg of

the wearer and provided with a longitudinal slot to receive the garment, a member 40 for coöperation with the plate for retaining the garment in the slot and including a bar adapted to pass through the slot and engage the garment, and a locking plate pivoted to the first named plate and engageable 45 with the bar to retain the latter in clamped engagement with the garment.

5. A garment supporter, including a supported garment engaging bar, a plate provided with a longitudinal slot to receive 50 the bar and one edge of the garment to be supported, and a member engageable behind the bar to retain the latter in position in the slot in clamped engagement with the garment.

6. In a garment supporter, a pad adapted to overlie the leg of the wearer, suspension elements attached to the pad, a longitudinally bowed plate overlying the pad and provided with a longitudinal slot to receive one end of the garment to be supported, a garment engaging member carried by the pad and including a bar which is off set from the pad and is adapted to pass through the slot and engage the garment, and a pivoted locking plate mounted on the longitudinally bowed plate adapted to be positioned behind the bar to retain the same in clamped engagement with the garment.

In testimony whereof I affix my signature in presence of two witnesses.

HENRY J. REED.
